[57] **CLAIM**

The ornamental design of a welding power supply,
substantially as shown and described.

DESCRIPTION

FIG. 1 is a top, front and side isometric view of a welding power supply showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof.
